UNITED STATES PATENT OFFICE.

JOHN W. NILSSON, OF BALFOUR, NORTH DAKOTA.

ATTACHMENT FOR TELEPHONES.

972,399.

Specification of Letters Patent. Patented Oct. 11, 1910.

Application filed November 16, 1909. Serial No. 528,314.

To all whom it may concern:

Be it known that I, JOHN W. NILSSON, a citizen of the United States, residing at Balfour, in the county of McHenry, State of North Dakota, have invented certain new and useful Improvements in Attachments for Telephones; and I do hereby declare the following to be a full, clear, and exact description of the invention, such as will enable others skilled in the art to which it appertains to make and use the same.

This invention relates to telephone circuits and more especially to a device for detecting a third party on a telephone circuit.

15 More particularly the invention is an attachment for telephones.

The principal object of the invention is to provide an audible signal which will indicate to a person using any one of the 20 telephones in a party line system the presence of an auditor at another telephone of that system.

Another object of the invention is to indicate to a person using any one of the 25 telephones in a party line system the number of the telephone answering his call, thereby giving information as to what telephone has responded to the call.

A third object of the invention is to provide means whereby the removal of the receiver from its fork will actuate a signal, the means being so arranged that it is impossible to tamper with the fork and give a 30 false signal.

35 With the above and other objects in view, the invention consists in general of an attachment for telephones arranged to give a signal when the receiver is removed from its fork, said attachment being provided with 40 means to prevent the simulation of the signal of one telephone by the signaling mechanism of another.

The invention further consists in certain 45 novel details of construction and combinations of parts hereinafter fully described, illustrated in the accompanying drawings, and specifically set forth in the claims.

In the accompanying drawings, like characters of reference indicate like parts in the 50 several views, and Figure 1 is a front elevation of an attachment for telephones constructed in accordance with this invention, the front of the casing of the device being removed to show the interior. Fig. 2 is a section on the line 2--2 of Fig. 1. Fig. 3 is a section on the line 3--3 of Fig. 1. Fig. 4 is

a detail section on the line 4--4 of Fig. 1. Fig. 5 is an enlarged detail view of the guard plate. Fig. 6 is an enlarged detail perspective of the bell actuating frame. 60 Fig. 7 is an enlarged detail showing the arrangement of one of the hammers.

The device has here been shown as applied to an ordinary telephone of the wall or box type such as is indicated by the letter A. 65 This telephone is equipped with the usual transmitter B and receiver C, all of these parts being of the ordinary and well known forms. Within the telephone casing is mounted the usual receiver fork 11 which is 70 pivoted to a bracket as indicated at 12. This receiver fork is provided with a contact block 13 which serves to close the usual line contacts 14. A spring 15 is mounted in the telephone casing beneath the receiver fork 75 and serves to raise the fork when the receiver is removed therefrom, the strength of the spring being so proportioned that the weight of the fork added to the weight of 80 the receiver will permit the spring to be depressed. Upon the fork 11 there is provided a clip having a pair of upstanding ears 16 through which passes a bolt 17 so that the device may be attached to any ordinary fork. This clip is further provided with 85 laterally extending ears 18 and 19. Attached to the clip is a plate 29 provided with a series of ratchet teeth 21 and this plate is of such dimensions as to completely cover the slot wherein the receiver fork operates. 90

Attached below the slot is a guide 22 for said plate and this guide is provided with an opening 23 which exposes a portion of the toothed edge of the plate. Adjacent this opening is mounted a spring pawl 24, the pawl being so positioned that the end thereof may drop into the opening and engage the ratchet teeth of the plate. Pivoted adjacent the guide is an arm 25 having a projecting 100 perforated ear 26. This arm is so arranged that when raised it presses against the end of the pawl and forces the same out of engagement with the ratchet teeth while when depressed it permits the pawl to engage the ratchet teeth. 105

At 27 is a cylinder wherein moves a piston 28 having a rod 29 extending downward therefrom. At the upper end of this cylinder there is provided a valve opening 30 wherein is seated a valve 31 attached to an arm 32 which is pivoted to a bracket 33 carried on the upper end of the cylinder and to 110

this bracket is also attached a spring 34 which is arranged to bear against the arm 32 and hold the valve down. In order to provide for opening this valve a certain amount 5 and thus permit the piston to move at the proper rate of speed the arm 32 is provided with a threaded opening wherethrough passes a screw 35 which bears against the upper end of the cylinder and serves as a 10 regulating screw for the valve.

Mounted on the back of the casing are brackets 36 provided with perforated ears 37 and through these ears passes a rod 38 forming a portion of the bell actuating frame. 15 This rod 38 is provided at its lower end with an eye 39 for purposes hereinafter to be described, and a U-shaped frame 40 having unequal legs is mounted on this rod and moves therewith. The lower leg of the U-shaped 20 frame 40 is connected to the lower end of the piston rod as clearly seen in Fig. 1 and the bight of this frame is provided with an upper series of pin receiving openings 41 and a lower series of pin receiving openings 42.

At 43 is indicated a bracket and on this bracket is mounted a lever 44 the longer arm of which is engaged in a loop on the end of the rod just described. Upon this lever 44 30 is mounted a sliding weight 46 which may be locked to the lever at any desired position by means of a thumb screw 47. The weight can thus be positioned so as to draw the piston downward in the cylinder and by regulating the position of the weight and the opening of the valve in the top of the cylinder the proper speed may be arranged for.

At 48 is indicated a bell of the ordinary type while at 49 is a gong made of a spiral 40 of tempered wire thus resembling the cathedral gong which is used in clocks. Adjacent the bell and gong is a transmitter 50 which is wired to the telephone circuit in the usual manner, and this transmitter is positioned in this manner so that the striking of the bell and gong will be plainly audible when the receiver of another telephone is held to the ear.

At 51 is a frame and on this frame are short shafts 52 upon which are supported levers 53, one arm of each of said levers projecting over the bell actuating frame and being arranged to be engaged by means of pins or pegs held in the apertures in that frame. 55 The other arms of these levers project over the opposite side of the bracket 51 and springs 54 bear against these arms and hold the levers normally in a horizontal position. Mounted on the shafts 52 are also other levers 55 each of which is provided with a hammer head 56. The other arm of each of these levers extends out over the spring 60 pressed end of the respective lever 53 and upon the outer of these arms are lugs 57 which engage over the ends of the spring

pressed levers so that as these levers are moved in one direction the hammers will be raised while when the lever is moved in the opposite direction to permit the passage of the pins upward the hammers are unaffected. 70 Now, it will be observed that the pins on the bell actuating frame are so arranged as to give a different signal for each of the telephones in a party line circuit and that as each of these pegs or pins actuates the hammer levers in their downward movement the levers will be caused to strike the bell and gong and thus give a sonant signal which may be heard at any other telephone on the line. Upon the end of the lever 44 opposite 80 to that which is attached to the bell actuating frame is a rod 58 which passes downward through an opening in the casing and through one of the lateral ears of the clip on the receiver fork. Just below the receiver fork this rod is threaded and is provided with a nut 59 which forms a stop whereby the lever is actuated to raise the frame which actuates the bells when the receiver fork is depressed. This rod also extends through the lateral ear on the pivoted arm which acts to disengage the pawl and on the bottom of this rod is a nut 60 which forms a stop whereby this arm is raised when the bell actuating frame moves downward, the stop being so positioned that the arm is not raised until the bell actuating frame has nearly completed its downward movement. Above this stop and in spaced relation thereto is a third stop 62 which is 95 so positioned that it acts to depress the arm when the bell actuating frame is raised and this stop is spaced at such a distance from the lower stop that it only depresses the pivoted arm when the bell actuating frame 100 has nearly reached the upper limit of its movement. Now, it will be observed that by means of this construction when the receiver is removed from its fork the spring of the receiver fork will raise this fork. It will also be noted that when the receiver fork is down the pivoted arm is disengaged from the pawl and the pawl allowed to engage the ratchet teeth so that the receiver fork cannot be worked up and down but of necessity 115 can only be moved upward so long as this arm is out of contact with the pawl. It will also be observed that the pawl is not released from the ratchet until the completion of the movement of the bell actuating frame so that the receiver fork cannot be again depressed after the receiver is removed until the complete signal has been given.

In order to prevent the signal from being given until the receiver fork is entirely raised certain locking mechanism is used for the lever 44. At 63 are certain brackets wherin is mounted a shaft 64 one end of which is provided with an arm 65 which, when the shaft is rotated, may engage be- 120 125

neath the end of the lever 44 adjacent the bell actuating frame. This arm is normally urged outward to this engaging position by means of a spring 66. One of the brackets 5 is also provided with a guide 67 where-through passes a trip bar or rod 68 which is secured to the clip on the receiver fork. The shaft is likewise provided with an arm 69 which, when the shaft is rotated, moves into 10 the path of the end of the trip bar. Now, when the receiver fork is depressed this trip bar is moved downward therewith and the shaft freed from restraint so that the latch end swings out underneath the lever 44. 15 When the receiver fork is raised it carries up with it the trip bar and at the upper end of its movement the trip bar strikes the arm on the shaft and moves the latch arm in. By this means when the receiver fork has 20 completed its upward movement the lever 44 is released from restraint and the weight 46 pulls the frame downward, thus actuating the signal. It will be observed that by means of this mechanism, the entire signal is rung every time the receiver is removed from 25 its fork and that until the signal is completed the receiver cannot be again depressed. It is thus impossible to so actuate the receiver fork as to cause an incorrect signal to be given. There has thus been provided a simple and efficient device of the kind described and for the purpose specified.

It is obvious that minor changes may be made in the form and construction of this 30 invention without departing from the material principles thereof. It is not therefore desire to confine the invention to the exact form herein shown and described, but it is wished to include all such as properly come 35 within the scope of the appended claims.

Having thus described the invention, what is claimed as new, is:—

1. In a device of the kind described, a signaling mechanism, a receiver fork, means 40 operatively connecting said mechanism and fork to set said mechanism for operation, said means operating to set said mechanism upon the depression of the fork, and elements arranged to prevent a second depression 45 of the fork until the signaling mechanism has completed its operation.

2. In a device of the kind described, a signaling mechanism, a receiver fork, means 50 operatively connecting said mechanism and fork to set said mechanism for operation, said means operating to set said mechanism upon the depression of the fork, elements arranged to prevent a second depression of the 55 fork until the signaling mechanism has completed its operation, and other elements arranged to hold the signaling mechanism from operation until the receiver fork completes its upward movement.

3. In a device of the kind described, a signaling mechanism, a receiver fork, an oper-

ating lever for said signaling mechanism, a clip on said receiver fork having an opening therethrough, a rod connected to said lever and slidale through the opening in the clip, a nut on said rod below the opening in the 70 clip, said lever, clip and rod forming means to set the signaling mechanism upon the depression of the fork, and elements arranged to prevent a second depression of the fork until the signaling mechanism has completed 75 its operation.

4. In a device of the kind described, a signaling mechanism, a receiver fork, an operating lever for said signaling mechanism, a clip on said receiver fork having an opening 80 therethrough, a rod connected to said lever and slidale through the opening in the clip, a nut on said rod below the opening in the clip, said lever, clip and rod forming means to set the signaling mechanism upon the depression of the fork, elements arranged to prevent a second depression of the fork until the signaling mechanism has completed 85 its operation, and other elements arranged to hold the signaling mechanism from operation until the receiver fork completes its upward movement.

5. In a device of the kind described, a signaling mechanism, a receiver fork, an operating lever for said signaling mechanism, a clip on said receiver fork having an opening therethrough, a rod connected to 90 said lever and slidale through the opening in the clip, a nut on said rod below the opening in the clip, said lever, clip and rod forming means to set the signaling mechanism upon the depression of the fork, a ratchet carried by said clip, a pawl mounted adjacent the ratchet and engageable therewith, a swinging arm pivoted adjacent the 95 pawl and provided with an opening through which said rod passes, said arm being arranged to engage beneath the pawl and raise the same as the arm is raised and to free said pawl as the arm is depressed, spaced 100 stops on said rod on opposite sides of the opening through the arm, the upper of said stops being arranged to depress the arm as the fork reaches the lower end of its movement, and the lower of said stops being arranged to raise the arm as the lever reaches 105 the completion of its signaling movement.

6. In a device of the kind described, a signaling mechanism, a receiver fork, an operating lever for said signaling mechanism, a clip on said receiver fork having an opening therethrough, a rod connected to 110 said lever and slidale through the opening in the clip, a nut on said rod below the opening in the clip, said lever, clip and rod forming means to set the signaling mechanism upon the depression of the fork, a ratchet carried by said clip, a pawl mounted 115 adjacent the ratchet and engageable therewith, a swinging arm pivoted adjacent the 120 pawl and provided with an opening through which said rod passes, said arm being arranged to engage beneath the pawl and raise the same as the arm is raised and to free said pawl as the arm is depressed, spaced 125 stops on said rod on opposite sides of the opening through the arm, the upper of said stops being arranged to depress the arm as the fork reaches the lower end of its movement, and the lower of said stops being arranged to raise the arm as the lever reaches the completion of its signaling movement.

pawl and provided with an opening through which said rod passes, said arm being arranged to engage beneath the pawl and raise the same as the arm is raised and to free said pawl as the arm is depressed, spaced stops on said rod on opposite sides of the opening through the arm, the upper of said stops being arranged to depress the arm as the fork reaches the lower end of its movement, and the lower of said stops being arranged to raise the arm as the lever reaches the completion of its signaling movement, and elements arranged to hold the signaling mechanism from operation until the receiver fork completes its upward movement.

7. In a device of the kind described, a signaling mechanism, a receiver fork, an operating lever for said signaling mechanism, a clip on said receiver fork having an opening therethrough, a rod connected to said lever and slidably through the opening in the clip, a nut on said rod below the opening in the clip, said lever, clip and rod forming means to set the signaling mechanism upon the depression of the fork, a ratchet carried by said clip, a pawl mounted adjacent the ratchet and engageable therewith, a swinging arm pivoted adjacent the pawl and provided with an opening through which said rod passes, said arm being arranged to engage beneath the pawl and raise the same as the arm is raised and to free said pawl as the arm is depressed, spaced stops on said rod on opposite sides of the opening through the arm, the upper of said stops being arranged to depress the arm as the fork reaches the lower end of its movement, and the lower of said stops being arranged

to raise the arm as the lever reaches the completion of its signaling movement, and elements arranged to hold the signaling mechanism from operation until the receiver fork completes its upward movement, said elements comprising a shaft adjacent said lever, an arm on said shaft adapted releasably to engage said lever and hold the same against movement when the signaling mechanism is set and the fork depressed, a trip bar carried by said fork, a second arm on said shaft having an end movable into the path of the trip bar when the fork is depressed and the lever locked, said second arm being engaged by the trip bar when the fork reaches the upper end of its movement whereby the shaft is rotated and the lever unlocked, and a spring normally urging the locking arm outward.

8. In a device of the kind described, a sliding frame, a series of pins carried by said frame, a bell, a hammer lever pivoted adjacent said frame, a short shaft whereon said lever is pivoted, a second lever mounted on said shaft and having an arm projecting over the frame to be engaged by the pins as the frame is moved, a spring normally holding the second lever horizontal, an arm formed on the first lever, and a lug on said arm projecting over the upper part of the spring pressed arm of the second lever whereby the second lever may be moved in one direction without affecting the first lever.

In testimony whereof, I affix my signature, in presence of two witnesses.

JOHN W. NILSSON.
